UNITED STATES PATENT OFFICE.

GEORGE H. BAKER, OF SEATTLE, WASHINGTON, ASSIGNOR OF ONE-HALF TO ORVILLE A. BANTA, OF SEATTLE, WASHINGTON.

WINDOW-SHADE FASTENER.

1,315,589.

Specification of Letters Patent.

Patented Sept. 9, 1919.

Application filed April 15, 1919. Serial No. 290,269.

To all whom it may concern:

Be it known that I, GEORGE H. BAKER, a citizen of the United States, residing at Seattle, in the county of King and State of Washington, have invented a new and useful Window-Shade Fastener, of which the following is a specification.

The present invention relates to window shade fasteners, the object being to provide a window shade fastener which will permit the shade being lowered from the top and which will retain the shade in any adjusted position on the window frame.

A second object of the invention is to provide a shade fastener which may be used upon any window frame construction without reconstructing the same and which will possess a neat appearance.

A further object is to provide a shade fastener which is easily operated and which will overcome the disadvantage of the curtain tearing from its fastenings as is often experienced with shades of the roller type.

An additional object of the invention is to provide a shade fastener which is simple and durable in use, consists of few parts that may be readily assembled and disassembled and which may be manufactured and sold at a minimum cost.

With the above and other objects and advantages in mind, the invention consists of combinations of elements, arrangement of parts, constructions and general assemblage which will be hereinafter enlarged upon and defined in the subjoined claims.

In the drawing: Figure 1 is a front elevation of the device in operative position on a window frame; Fig. 2 is an end elevation of the same; Fig. 3 is an enlarged view of one of the locking devices and parts associated therewith partly in section; and Fig. 4 is a perspective of one of the locking plates.

Referring to the drawing wherein like characters of reference indicate like parts the numeral 5 denotes a window frame of any usual construction to which are secured the vertical guide rods 6 upon opposite sides thereof. These rods are formed with eyes 7 at their upper ends which are secured to the window frame by fastenings 8. These rods are spaced from the window frame by bending the upper ends at right-angles as indicated at 9, the rods being extended through eyes 10 mounted on the window frame adjacent the lower ends of the rods.

A vertically movable bar 11 is provided to which is attached the shade 12 and has notches 13 formed in its upper edge at its opposite ends and further provided with openings 14 in these ends which receive the guide bars 6.

Locking plates 15 are slidably mounted upon the guide rods 6 and are provided with longitudinal slots 16 at their inner ends in which pins 17 carried by the sash are engaged. These pins 17 are bent at right-angles to retain the plates in their relative position.

Expansible coil springs 18 are seated in the notches 13 and encircle the guide rods 6 and bear against the under face of the plates 15 to normally retain the same at an angle to the sash bar so that the plates will bind on the guide rods and thus retain the bar against displacement.

Flexible elements 19 are attached to the outer ends of the locking plates by means of which the plates are moved to a horizontal position so that the same will be free to slide on the guide rods 6. It will be manifest that the eyes 10 not only serve to retain the guide rods 6 in position but serve as stops to limit the downward movement of the slidable bar.

The embodiment of the invention herein set forth and illustrated is considered the preferred construction but it will be understood that the construction may be modified in many respects and that my limits of modification are only governed by the subjoined claims.

What is claimed is:—

1. A shade fastening comprising vertically disposed guide rods arranged upon opposite sides of the window, a shade attaching bar slidably engaged with the guide rods, an oppositely inclined locking plate disposed at each end of the bar and having pivotal and slidable connection therewith, an expansible coil spring encircling each of the guide rods and resting upon the bar and urging the locking plates to a position where the same will bind against the guide rods, and means for moving the locking plates to a horizontal position against the tension of the coil springs and to lower the shade bar.

2. A window shade fastening comprising guide rods disposed upon opposite sides of the window, a shade carrying bar slidably engaged with the rods, locking plates slid-

able on the rods and provided with longitudinal slots at their inner ends, pins carried by the shade-carrying bar and disposed in the slots to permit the plates to move vertically and expansible springs bearing against the outer ends of the shade carrying bar, and flexible elements depending from the plates for moving the same against the tension of the springs to lower against the shade bar.

3. In a window shade fastener, a pair of vertical guide rods arranged upon opposite sides of the window, a shade carrying bar having openings in its opposite ends which receive the guide rods and further provided with notches in its upper face and at its ends, locking plates slideable on the guide rods and having slideable and pivotal connection with the shade carrying bar, coil springs encircling the guide rods and bearing against the inner ends of the plates to retain the same in binding engagement with the guide rods, and flexible elements depending from the plates for moving the same to a position where they will be free to slide on the guide rods.

4. In a window shade fastener, a pair of guide rods arranged upon opposite sides of the window frame and offset from the same, eyes mounted at the lower ends of the rods and receiving the same, a shade carrying bar slideable on rods, locking plates slideable on the rods and having longitudinal slots in their inner ends, pins carried by the shade carrying bar and engaging in the slots to

permit the plates to move vertically and horizontally, springs bearing against the outer ends of the plates and the shade carrying bar, and flexible elements depending from the plates for moving the same against the tension of the springs.

5. A window shade fastener comprising a pair of guide rods disposed upon opposite sides of the window, a shade carrying bar slidably engaged with the rods, locking plates slideable on the rods and provided with longitudinal slots at their inner ends, pins at each end of the bar and having inwardly directed longitudinally curved upper ends, the slotted ends of the plates being engaged with the pins, springs bearing against the outer ends of the plate and the shade carrying bar and normally retaining the plates in an angular position to cause the same to bind on the guide rods and to dispose the slotted ends of the plates on the curved ends of the pins, the curved ends of the pins binding against the adjacent end walls of the slots when the plates are in said angular position, and flexible elements for moving the plates to a horizontal position and to lower the shade bar.

In testimony that I claim the foregoing as my own, I have hereto affixed my signature in the presence of two witnesses.

GEORGE H. BAKER.
